US0D1078540S

(12) **United States Design Patent** (10) **Patent No.:** **US D1,078,540 S**
(45) **Date of Patent:** **** Jun. 10, 2025**

(54) **VEHICLE**

(71) Applicant: **Club Car, LLC**, Evans, GA (US)

(72) Inventors: **Daniel Russ Dykstra**, Augusta, GA (US); **Nikolas Anthony Bryan-Dunaway**, Grovetown, GA (US); **Gregory James Lacock**, Augusta, GA (US); **Hayden Adam Lynch**, Harlem, GA (US); **Jonathan Eugene Sturm**, LaGrange, IN (US); **William Clayton Martin**, Stillwater, OK (US)

(73) Assignee: **Club Car, LLC**, Evans, GA (US)

(**) Term: **15 Years**

(21) Appl. No.: **29/842,753**

(22) Filed: **Jun. 15, 2022**

(51) LOC (15) Cl. **12-02**

(52) U.S. Cl. **USPC 12/16**

(58) **Field of Classification Search**

USPC D21/433, 434, 533, 535; D12/1, 82-100, D12/164

(57) **CLAIM**

The ornamental design for a vehicle, as shown and described.

DESCRIPTION

FIG. 1 is a perspective view of a vehicle showing our new design;

FIG. 2 is a front view of the vehicle of FIG. 1;

FIG. 3 is a rear view of the vehicle of FIG. 1;

FIG. 4 is a left side view of the vehicle of FIG. 1;

FIG. 5 is a right side view of the vehicle of FIG. 1;

FIG. 6 is a top view of the vehicle of FIG. 1; and,

FIG. 7 is a bottom view of the vehicle of FIG. 1.

The portions of the vehicle shown in broken lines form no part of the claimed design.

1 Claim, 6 Drawing Sheets
